UNITED STATES PATENT OFFICE.

OTTO MEINSHAUSEN, OF CHICAGO, ILLINOIS.

LIQUID-COOLING APPARATUS.

SPECIFICATION forming part of Letters Patent No. 594,545, dated November 30, 1897.

Application filed June 3, 1897. Serial No. 639,234. (No model.)

To all whom it may concern:

Be it known that I, OTTO MEINSHAUSEN, a citizen of the United States, residing at Chicago, in the county of Cook and State of Illinois, have invented a new and useful Improvement in Liquid-Cooling Apparatus, of which the following is a specification.

My invention relates to liquid-cooling apparatus in which the liquid to be cooled is caused to flow an extended course through a conduit in one direction, the said conduit being surrounded by or surrounding a second conduit, through which a cooling fluid is caused to flow.

While my invention may be employed for cooling any kind of liquid, it is intended more especially for use as a beer or wort cooler.

My object is to provide apparatus of improved construction in which the liquid to be cooled travels an extended course in one direction under the chilling influence of a cooling fluid flowing in the opposite direction, the apparatus being particularly compact and effective in operation and at the same time easy to clean.

In the drawings, Figure 1 is a broken end view in the nature of a diagram of wort-cooling apparatus of my improved construction; Fig. 2, an enlarged broken longitudinal section taken on line 2 of Fig. 1 and showing one of the series of cooling devices; and Figs. 3 and 4, sections taken, respectively, on lines 3 and 4 of Fig. 2.

A A are cooling devices, all of which are constructed as shown in detail in Figs. 2, 3, and 4. Each device A is formed with an outer shell comprising a central cylinder *t*, end cylinders *s* *r*, and heads *q* *p*. In the head *p* is a cleaning-opening *p'*, over which fits a cap-plate *p*², held in place by a flanged ring *p*³, rendering the opening gas-tight. Fitting between the cylinders *r* *t* is a diaphragm *n*, having a circumferential flange *n'*, at which it is secured between flanges on the said cylinders. The diaphragm *n* is formed with a central tubular extension *n*², having an end *n*³, provided with a comparatively large central opening *n*⁴, surrounded by a series of smaller openings *n*⁵. On opposite sides of the tubular portion *n*² and formed integral with the diaphragm are passages *n*⁶, extending from the flanged face of the diaphragm

nearly to the opposite end of the space surrounded by the tubular extension *n*². The flange *n'* within the cylinder is provided on opposite sides of the passages *n*⁶ with a series of openings *n*⁷. Extending through a stuffing-box *q* in the head *q* is a pipe *m*, rendered flaring on the inner side of the cylinder and there provided with an outer circumferential shoulder *m'* and an end plate *m*², which latter is provided with a series of openings corresponding with the openings *n*⁴ *n*⁵ in the diaphragm *n*. In the cylinder is a sleeve *l*, provided at one end with a flange *l'*, at which it is fastened between adjacent flanges on the shell-sections *t* *s*. At its opposite end the sleeve *l* fits tightly over the annular shoulder *m'* of the pipe *m*. An inner cylinder *k* fits at one end in the tubular section *n*² and at its opposite end passes through the sleeve *l* and fits over the shoulder *m'*, all the joints being tight. Within the inner cylinder is a central pipe *k'*, surrounded by a series of smaller pipes *k*². The pipe *k'* at one end is fastened in the opening *n*⁴ of the diaphragm and at its opposite end is fastened in the corresponding opening in the plate *m*². The pipes *k*² are fastened at one end in the openings *n*⁵ of the diaphragm and at their opposite ends in the corresponding openings in the plate *m*². Between the inner cylinder *k* and outer shell is a series of pipes *i*, fastened at one end in the openings *n*⁷ in the flange *n'* and fastened at their opposite ends in corresponding openings *l*² in the flange *l'*.

Extending into the shell-section *t* is a pipe or conduit *B*. *B*' is a pipe or conduit extending through the shell-section *s* and into the cylinder *k*, thus communicating with the interior of the latter. *C* is a pipe or conduit extending through the shell-section *s* only. The interior of the shell, it will be understood, is separated by the internal walls into chambers or compartments *x* *x'* *y* *y'*. The chamber *x* surrounds the inner cylinder, and the chamber *x'* surrounds the pipes *k'* *k*² in the inner cylinder. The said two chambers communicate through the passages *n*⁶. The chambers *y* *y'* are at opposite end portions of the shell and communicate with each other through the pipes *i*.

The wort or beer to be cooled enters through the pipe *m* and passes through the pipes *k'* *k*²

to what I term the "primary" end chamber y . From the chamber y it passes through the pipes i to what I term the "secondary" end chamber y' , whence it escapes through the pipe C . The cooling fluid enters at B , filling the chamber x , surrounding the inner cylinder, and enveloping the pipes i . From the chamber x the cooling fluid flows through the passages n^6 to the chamber x' , where it envelops the pipes $k' k^2$, escaping through the pipe B' . The wort or beer as it enters the device is acted upon by the cooling liquid just escaping from the device, and as it flows to the outlet C the wort or beer is subjected to the cooling influence of the cooling fluid which has just entered the device.

Wort or beer to produce the best results in the final product should be cooled more or less gradually and should not be subjected to a too sudden chilling. For this reason, and also to obtain the best results from the cooling fluid, it is advisable to cause the beer or wort to be acted upon at first by the cooling fluid after the latter has absorbed heat and finally by the cooling fluid at its lowest temperature.

My aim in devising the present device has been to render it as compact as possible and at the same time cause the beer or wort to pursue the longest possible course under the influence of the cooling fluid, at the same time permitting the device to be readily cleaned when desired.

When it is desired to clean the device, the plate p^2 should be removed to permit a suitable pipe-cleaner to be passed back and forth through the pipes k', k^2 , and i . The chamber y may be readily cleaned at the same time and the chamber y' may be flushed out or scrubbed, in which latter event the head q may be removed to give more ready access to the chamber y' .

In Fig. 1 I have shown my devices coupled together in series below a hop-jack D . The wort enters the first device through a pipe D' , passing thence through the pipe C to the next device to the end of the first or upper series of devices, from the last of which it passes downward through a pipe C' to the first of a second series of cooling devices A' . From the end of the second series it passes downward through a pipe C^2 to a lower series of devices A^2 , from the last of which it escapes through a pipe C^3 and is collected. Through

the pipes $B B'$ of the upper series of devices 55 I pass cold water to effect the initial cooling of the wort. Through the next lower series I pass brine from a suitable refrigerating apparatus to effect further cooling of the wort, and through the lower series of devices I expand ammonia-gas to complete the cooling and bring the wort down to the desired low temperature. The course of the wort is such that initially its temperature is influenced by water comparatively warm and finally by ammonia-gas at the lowest temperature which it is desirable to employ. 65

While I prefer to construct my improved apparatus in all its details as shown and described, the construction may be modified 70 without departing from the spirit of my invention as defined by the claims.

What I claim as new, and desire to secure by Letters Patent, is—

1. In a liquid-cooler, the combination of a 75 shell, an inner cylinder and inner walls forming together primary and secondary end chambers and intermediate and intercommunicating concentric chambers, a conduit extending into one end of the shell, a series of 80 straight and parallel pipes extending from said conduit through the inner intermediate chamber to the primary end chamber, a series of straight and parallel pipes extending from one end chamber to the other through the 85 outer intermediate chamber, a conduit communicating with the secondary end chamber, and conduits communicating respectively with the inner and outer intermediate chambers, substantially as and for the purpose set 90 forth.

2. In a liquid-cooler, the combination of the outer shell, inner cylinder k and inner cylinder ends $l n$ forming together end chambers $y y'$ and intermediate concentric chambers $x x'$, a conduit m at one end of the shell, pipes $k' k^2$ extending from said conduit through the chamber x to the chamber y , pipes i extending between the chambers $y y'$, through the chamber x , and conduits communicating respectively with the chambers $x x'$ and y , all constructed and arranged to operate, substantially as described. 95 100

OTTO MEINSHAUSEN.
